DRIVING MECHANISM

Nathan M. Lower, Tuckahoe, N. Y., assignor to
The Standard Stoker Company, Incorporated,
a corporation of Delaware

Application December 21, 1934, Serial No. 758,581

5 Claims. (Cl. 74—389)

My invention relates to driving mechanism and especially to such mechanism for use in driving conveyors. More particularly, this invention relates to conveying systems of the type employing several conveyors driven by gearing, the conveyors being related with the gearing in a manner so that when the operation of one conveyor is interrupted, the other conveyor or conveyors may continue to operate.

10 The principal object of my invention is to provide a driving mechanism including a drive shaft and a pair of driven shafts, the driving mechanism being characterized by at least a pair of reduction gear trains, one for operatively connecting its respective driven shaft and the common drive shaft, and means on the common drive shaft whereby one gear train may be selectively connected to or disconnected from its operative relation with the drive shaft.

15 Another object of my invention is to provide, in a conveying system of the heretofore described type, gearing for operating the several conveyors in the above described manner, the gearing including a reduction gear train for operating at least one of said conveyors and another reduction gear train arranged to operate the remaining conveyor or conveyors independently of said first named gear train, each gear train being operable by a common drive shaft.

20 More specifically, it is an object of this invention to provide a conveying system of the above described construction and wherein the drive shaft has mounted thereon at least a pair of pinion gears, one for each reduction gear train, one of the pinion gears at all times being in driving relation with said drive shaft while the other pinion gear is slidable along the drive shaft and arranged to engage the first named pinion gear.

25 A still further object of this invention resides in the provision of the above described gearing for a conveying system which employs at least a pair of conveyor screws having independent drive connections and wherein the driving shaft for one conveyor screw passes freely through the other conveyor screw.

These and other objects, such as the particular construction of the parts and their novel relation one with another, will be apparent as the following description is read in connection with the accompanying drawing, in which,

30 Fig. 1 is a vertical medial section through adjacent portions of a locomotive and tender provided with a stoker to illustrate an embodiment 55 of my invention; parts of the stoker are shown

in vertical medial section while other portions are in side elevation;

Fig. 2 is an enlarged fragmentary view of my invention taken on the line 2—2 of Fig. 1;

Fig. 3 is a sectional view taken on the line 3—3 of Fig. 2;

Fig. 4 is a sectional view taken on the line 4—4 of Fig. 3; and

Fig. 5 is an enlarged fragmentary view of a portion of Fig. 1.

Referring now to Figures 1 to 5, inclusive, which illustrate the invention as applied to a locomotive stoker, 10 represents the locomotive having a firebox 11 provided with a backwall 12 in which there is the usual firing opening 13. At 14 is indicated the tender which is coupled to the locomotive at 15. The tender 14 includes the deck 16, a fuel bin 17 above the deck and a compartment 18 therebelow in which compartment is mounted the rear or trough conduit 19 of the stoker mechanism which is generally indicated by S.

The stoker mechanism includes the rear or trough conduit 19 which may be rigidly mounted beneath the fuel bin 17 to receive fuel therefrom through the aperture 20 in the deck 16. Rigidly mounted on the locomotive is an inclined elevator conduit 21 which communicates with the firebox 11 through the firing opening 13 and has associated therewith a fuel distributing means 22 which receives the fuel discharged from the elevator conduit 21 and projects it to all parts of the firebed. At its rearward end, the elevator conduit is connected by a ball and socket joint 23 to an intermediate conduit 24, comprising the telescopically related forward and rearward sections 25 and 26, respectively, the latter being connected to the forward end of the rear or trough conduit 19 by a ball and socket joint 27.

Housed within these conduits is a system of conveyors generally indicated by C and including a conveyor screw 28 in the trough conduit 19, an intermediate conveyor screw 29 in the conduit 24 and an elevator screw 30 in the inclined conduit 21. The forward end of the intermediate conveyor screw 29 is connected to the lower end of the elevator screw 30 by a universal joint structure 31, while the rearward end of the intermediate conveyor screw 29 receives fuel from the forward end of the conveyor screw 28 but has a separate drive connection therefrom, which will be described more fully as the specification proceeds.

The driving mechanism for the conveyor screws

is disposed at the rear of the trough conduit 19 within a casing 32 and includes a reduction gear train 33 for operating the conveyor screw 28 and a reduction gear train 34 for operating the intermediate conveyor screw 29 and its connected elevator screw 30. Comprising the gear train 33 is a pinion 35 meshing a gear 36 which is keyed or otherwise fixed to a shaft or hollow hub 37. This hollow hub 37 is journaled in a bearing 38 and has a flange 39 through which bolts 40 are passed for securing the conveyor screw 28 thereto. The gear train 34, likewise, comprises a pinion gear 41 which meshes with a gear 42, the latter being keyed or otherwise fixed to a shaft 43 which passes through the hollow hub 37 and is journaled therein.

In substantial axial alignment with the shaft 43 and extending through the hollow hub 44 of the conveyor screw 28 is another shaft 45 which is coupled to the shaft 43 by a sleeve 46 and has the opposite end projecting beyond the forward end of the conveyor screw 28. To this latter end of the shaft 45 is fastened a jaw member 47, forming one element of a universal joint 48 which connects the rearward end of the intermediate conveyor screw 29 to the shaft 45 within the ball and socket joint 27.

It will be observed from Fig. 2 that the pinion gear 41 of the gear train 34 is fixed to the drive shaft 49 by a key 50 while the pinion gear 35 of the gear train 33 is freely mounted on the drive shaft 49. This drive shaft receives power from a suitable prime mover (not shown) by means of shafting 51 (Fig. 1). At their adjacent side faces, the pinion gears 35 and 41 are each provided with projections 52 which are engageable during the normal operation of the conveying system whereby the pinion gears 35 and 41 operate their respective gear trains 33 and 34 in unison, thereby driving the entire conveying system.

During operation of the conveying system, extraneous matter in the fuel will often times lodge between the crusher 53, a portion of which is shown in Fig. 1, and the flights of the conveyor screw 28, causing the entire conveying mechanism to become inoperative. In order that the operation of at least the elevator screw 30 may be continued during these emergencies, means have been provided to disconnect the conveyor screw 28 and its gear train 33 from their operative relation with the drive shaft 49. This means includes the described relation of the pinion gears 35, 41 and the added means for causing selective engagement or disengagement of these pinion gears.

This last named means includes a forked yoke 54 which is fixed to a rod 55 by a pin 56 and engages a groove 57 in the pinion gear 35. Coupled to the rod 55 is an extension rod 58, which may be manipulated by the stoker operator in a manner which will cause the yoke 54 to engage or disengage the pinion gears 35, 41. The yoke 54 has therein a pair of notches 59, 60 (Fig. 5) which are engageable by a spring actuated detent 61 for retaining the pinion gear 35 in or out of engagement with the pinion gear 41.

It will be apparent that when the stoker operator draws the extension rod 58 forwardly, the pinion gear 35 becomes disengaged from the pinion gear 41 whereby the gear train 33 and the connected conveyor screw 28 will no longer be operatively connected to the drive shaft 49. The pinion gear 41 will thus be free to drive the gear train 34 for operating the intermediate conveyor screw 29 and its connected elevator screw 30.

The stoker operator may then swing open the hinged cover 62 which is over the hopper 63 in the elevator conduit 21 and manually deliver a charge of fuel thereto, whereby the elevator screw 30 will continue delivery of fuel to the distributing means 22. Upon removing the extraneous material, the extension rod 58 is pushed rearwardly causing the yoke 54 to engage the pinion gear 35 with the pinion gear 41, whereupon normal operation of the conveying system is resumed.

It will be observed from Fig. 2 that the pinion gear 35 functions as a clutch member for selectively connecting or disconnecting the gear train 33 and the power shaft 49. Since the power shaft 49 rotates at a speed which is considerably greater than the speed of any other shaft of the drive mechanism, it is of considerable advantage to relate the clutch member or movable pinion gear 35 on the shaft which has a relatively high speed, because the torsional strains which tend to shear the interengaging projections 52 of the pinion gears are considerably less on the high speed shaft than the torsional strains of the slower moving shafts. The engagement and disengagement of the projections 52 of the pinion gear is accomplished with greater ease because of the relatively low torque. By this construction, the clutch member or pinion gear 35 can be made smaller than otherwise possible and also its life is increased considerably.

While the drive mechanism of my invention has been described in connection with a stoker conveying system, it is apparent that its use is not limited to such structures but is applicable for driving other devices, substantially as defined in the following claims.

I claim:

1. In a drive mechanism, the combination including a drive member, a pair of driven members, one of said driven members forming a support for the other, a gear train arranged to operatively connect said drive member with one of said driven members, a gear train arranged to operatively connect said drive member with the other driven member, each gear train comprising a pinion gear upon said drive member and a gear meshing therewith and being operatively connected to its respective driven member, one of said pinion gears being fixed to said drive member for rotation therewith, the other pinion gear being loosely mounted upon said drive member, each of said pinion gears being provided with interengageable projections on adjacent sides, and means for sliding one of the pinion gears along said drive member to cause selective engagement or disengagement of the projections of said pinion gears.

2. In a drive mechanism, the combination including a drive member, a pair of driven members, one of said driven members forming a support for the other, a gear train arranged to operatively connect said drive member with one of said driven members, a gear train arranged to operatively connect said drive member with the other driven member, each gear train comprising a pinion gear upon said drive member and a gear meshing therewith and being operatively connected to its respective driven member, one of said pinion gears being fixed to said drive member for rotation therewith, the other pinion gear being loosely mounted upon said drive member, each of said pinion gears being provided with interengageable projections on adjacent sides, and means for sliding the loosely mounted pinion gear along said drive member to cause selective engagement or disengagement of the projections of

engagement or disengagement of the projections of said pinion gears.

3. In a drive mechanism, the combination including a drive shaft, a driven shaft, gearing connecting said drive shaft with said driven shaft comprising a pinion gear fixed to said drive shaft for rotation therewith, and a gear meshing with said pinion gear operatively connected to said driven shaft, a driven member mounted on said driven shaft coaxially therewith, gearing connecting said drive shaft with said driven member comprising a pinion gear loosely and slidably mounted upon said drive shaft, and a gear meshing with such pinion operatively connected to said driven member, each of said pinion gears being provided with interengageable projections on their adjacent sides, and means for sliding the second named pinion gear along said drive shaft to cause selective engagement or disengagement of the projections of said pinion gears.
4. In a drive mechanism, the combination including a drive member, a pair of driven members one of which forms a journal for the other, a gear train arranged to operatively connect said drive member with one of said driven members, a gear train arranged to operatively connect said drive member with the other driven member, each gear train comprising a pinion gear upon said drive member and a gear meshing therewith and being operatively connected to its respective driven member, one of said pinion gears being fixed to said drive member for rotation therewith, the other pinion gear being loosely mounted upon said drive member, each of said pinion gears being provided with interengageable projections on their adjacent sides, and means for sliding the loosely mounted pinion gear along said drive member to cause selective engagement or disengagement of the projections of said pinion gears.

driven member, one of said pinion gears being fixed to said drive member for rotation therewith, the other pinion gear being loosely mounted upon said drive member, each of said pinion gears being provided with interengageable projections on their adjacent sides, and means for sliding one of the pinion gears along said drive member to cause selective engagement or disengagement of the projections of said pinion gears.

5. In a drive mechanism, the combination including a drive member, a pair of driven members one of which forms a journal for the other, a gear train arranged to operatively connect said drive member with one of said driven members, a gear train arranged to operatively connect said drive member with the other driven member, each gear train comprising a pinion gear upon said drive member and a gear meshing therewith and being operatively connected to its respective driven member, one of said pinion gears being fixed to said drive member for rotation therewith, the other pinion gear being loosely mounted upon said drive member, each of said pinion gears being provided with interengageable projections on their adjacent sides, and means for sliding the loosely mounted pinion gear along said drive member to cause selective engagement or disengagement of the projections of said pinion gears.
